Watson E. Coleman *Attorney*

UNITED STATES PATENT OFFICE.

JOHN M. THOMAS, OF MARION, IOWA.

HAT AND UMBRELLA HOLDER.

1,420,891.

Specification of Letters Patent. Patented June 27, 1922.

Application filed April 30, 1921. Serial No. 465,733.

To all whom it may concern:

Be it known that I, JOHN M. THOMAS, a citizen of the United States, residing at Marion, in the county of Linn and State of Iowa, have invented certain new and useful Improvements in Hat and Umbrella Holders, of which the following is a specification, reference being had to the accompanying drawings.

10 This invention relates to article holders and particularly to hat and umbrella holders.

The object of the invention is to provide a device of this character capable of being 15 readily applied to the bottom of a seat or like support, and wherein a hat as well as an umbrella may be supported within convenient reach.

Another object is to provide a device of 20 this character wherein hats of various sizes and shapes may be conveniently supported by the holder, as it is capable of yielding to accommodate the hat.

A still further object is to provide a device 25 of this character wherein the parts arranged to support hats also include means for supporting an umbrella substantially in a horizontal position in spaced relation to the hat.

With these and other objects in view the 30 invention consists in the improved construction and arrangement of parts to be hereininafter more particularly described, full claimed and illustrated in the accompanying drawings in which:—

35 Figure 1 is a bottom plan view of the support, showing the invention applied.

Figure 2 is a side elevation partly in section.

40 Figure 3 is a side elevation looking from the opposite direction to that of the structure shown in Figure 2 partly in section, and

Figure 4 is an end elevation.

45 Referring to the drawings 4 designates a support such as the seat of a church pew, theater chair or shelf. The holder comprises two parts 5 and 6, each part consisting of a single length of resilient material such as wire, the part 5 having its end portion 7 extended back upon the body portion of said 50 length with the extremity of said end inclined upwardly and then extended substantially in spaced parallel relation to the body portion of said length. In this way the bend of the end portion 7 permits yielding 55 movement of the body member. The end

portion 8 of the part or length 5 is extended in the opposite direction to that of the end portion 7 substantially in angular relation to the body portion of said length and then outwardly and upwardly to form a loop 9, 60 said loop being disposed substantially at right angles to the curve end portion 7 and the body portion of the part 5. The extremity 10 of the end portion 8 is inclined or extended upwardly and then disposed 65 substantially in parallel relation to the body portion of the length 5 to provide supporting means for said end.

A pair of socket members 11 are provided, each of said members consisting of a body 70 member having a slot 12 extending transversely thereof and adjacent one end of the body member, the opposite end and intermediate portion of the body member having openings for the reception of screws 13 or 75 like fastening means. These sockets are secured to the bottom of the support 4 substantially in offset relation to each other, one of said members being adapted to receive the extremity of the end portion 7 80 while the other member is adapted to receive the extremity of the end portion 8 of the part 5. It will be noted that the extremities of the part 5 project a considerable distance beyond the socket member so 85 as to permit said part or length to adjust itself when in use and prevent injury to the article supported thereby.

The remaining part 6 of the device consists of a length of resilient material, preferably wire, having its end portion 14 curved slightly beyond the plane of the body portion of the length, and having its extremity 15 formed substantially into an eye adapted to receive a screw 16 or like fastening means. 90 The opposite end portion 17 of the part 6 is curved substantially back upon the body portion of part 6, extended upwardly substantially at right angles to the body member and then extended in parallel relation 100 to the body member and bent to provide an eye 18 adapted to receive a screw 19 or like fastening means. The remainder of said end portion is then extended downwardly below the body member of the part 6 and then upwardly to form a relatively large hook 20, the hook 20 being disposed substantially on alignment with the loop 9 of the part 5. It will be noted that the body portions of each 105 of the parts 5 and 6 are disposed in spaced 110

relation to the support 4 through the novel arrangement of the end portions of said parts.

In view of the curvature of the end portions of these parts, a hat of any size may be readily engaged with the parallel body portions 5 and 6, and as these parts are resilient, they will readily yield to the shape and size of the hat without causing injury or permitting the hat to become accidentally disengaged. At the same time, the end portion 8 of the part 5 and the end portion 17 of the part 6 are curved in opposite directions so as to provide an unobtrusive entrance to the holder for the hat. It will be noted that the entrance to the loop 9 of the part 5 is restricted so as to prevent accidental disengagement of the article positioned in the loop. The loop as above described is disposed substantially in alignment with the hook 20 and is adapted to receive one end of an umbrella or cane, the handle of the umbrella or cane being engaged with the loop 9 so as to position the same substantially in a horizontal position beneath the support in spaced relation to the floor and the hat supported by the parts 5 and 6.

From the foregoing it will be readily seen that this invention provides a novel device for supporting hats of various sizes as well as umbrellas and canes, it being possible, in view of the particular construction of the loop 9 and hook 20, for the device to support one or more umbrellas or canes. Another important feature is that the end portion 7 of the part 5 and end portion 14 of the part 6 are so positioned that they do not interfere with each other so that the yieldable movement of the device is not interfered

with. In addition to this the parts 5 and 6 can be constructed from a single length of resilient material and while these parts are not connected to each other, they cooperate to efficiently support an article engaged therewith, and by making the parts 5 and 6 separate they can be readily adjusted to suit the purpose of the user.

What is claimed is:—

A holder of the character described comprising a base member, a resilient supporting member having one end portion thereof curved back upon the body portion of said member, and then extended in angular relation to said member and secured to the base member, the opposite end portion of said member being extended in the opposite direction to the first mentioned end portion of said supporting member and provided with a loop, the end portion of the loop being extended beyond the body portion of said supporting member and secured to the base member, a second resilient supporting member having one end portion extended in angular relation to the body portion of said supporting member secured to the base member adjacent the first mentioned end of the first mentioned supporting member, the opposite end of the second mentioned supporting member being curved to one side and then extended upwardly and secured to the base member, the remainder of the last mentioned end portion being extended upwardly and formed into a hook, said hook being disposed substantially in alignment with the loop of the first mentioned supporting member.

In testimony whereof I hereunto affix my signature.

JOHN M. THOMAS
